HANGER FOR SKIN DIVER EQUIPMENT

Donald G. Papineau, 26 Willow Road,
Greenville, R.I. 02828

Filed Apr. 29, 1968, Ser. No. 11,658

Term of patent 14 years

Int. Cl. D6—07

U.S. Cl. D80—8

FIG. 1 is a rear elevational view of a hanger for skin diver equipment showing my new design;

FIG. 2 is an elevational view taken from one side thereof;

FIG. 3 is an elevational view taken from the side opposite that shown in FIG. 2;

FIG. 4 is a top plan view thereof;

FIG. 5 is a bottom plan view thereof; and

FIG. 6 is a fragmentary front elevational view of an end thereof.

I claim:

The ornamental design for a hanger for skin diver equipment, substantially as shown.
